CLAIM

The ornamental design for a wheel loss sensor and bracket, as shown and described.

DESCRIPTION

FIG. 1 is a bottom perspective view of a wheel loss sensor and bracket;

FIG. 2 is a top perspective view thereof;

FIG. 3 is a front view thereof;

FIG. 4 is a left-side view thereof;

FIG. 5 is a back view thereof;

FIG. 6 is a right-side view thereof;

FIG. 7 is a bottom view thereof; and,

FIG. 8 is a top view thereof.

The broken lines depict portions of the wheel loss sensor and bracket that form no part of the claimed design.
